UNITED STATES PATENT OFFICE.

WILLIAM PEARCE, OF PLANTSVILLE, ASSIGNOR TO HIMSELF, AND M. N. WOODRUFF AND N. A. BARNES, BOTH OF SOUTHBURY, CONN.

DIE FOR FORGING OX-SHOES.

SPECIFICATION forming part of Letters Patent No. 314,193, dated March 17, 1885.

Application filed September 2, 1884. (No model.)

To all whom it may concern:

Be it known that I, WM. PEARCE, of Plantsville, in the county of Hartford, and in the State of Connecticut, have invented certain new and useful Improvements in the Manufacture of Ox-Shoes; and I do hereby declare that the following is a full, clear, and exact description thereof, reference being had to the accompanying drawings, in which—

10 Figure 1 is a perspective view of the upper and lower dies used by me in the forging of ox-shoes having parallel calks. Fig. 2 is a like view of the same as arranged for forging the ordinary form of shoe. Fig. 3 is a perspective view of a blank and a completed shoe as left by the dies shown in Fig. 1. Fig. 4 is a like view of the same as left by the dies shown in Fig. 2. Fig. 5 is a section of the dies through the longitudinal axis of one of 15 the recesses, said dies being closed together upon a bar of iron; and Figs. 6 and 7 are respectively perspective views of the trimming-dies shown in connection with the dies shown in Figs. 1 and 2.

20 Letters of like name and kind refer to like parts in each of the figures.

The object of my invention is to enable ox-shoes to be quickly and easily produced from a straight bar by means of dies, to which end 25 said invention consists, principally, in the construction of the dies whereby a number of shoes may be forged from a straight bar at one heat, substantially as and for the purpose hereinafter shown.

30 It consists, further, in the series of dies used for forging a shoe, substantially as and for the purpose hereinafter set forth.

It consists, finally, in combining with forging-dies, constructed substantially as shown, 35 trimming-dies which are adapted to receive the sprue-connected blanks and to trim from each the surplus metal, substantially as and for the purpose hereinafter described.

In the carrying into effect of my invention 40 I employ two forging-dies, A and B, which, for convenience, are formed within one block of metal and are arranged side by side, but may, if desired, be formed separately. The first of said dies, A, has the general size and 45 shape of the desired shoe C, and is provided

50 with a small half-round rib, a, that partly forms the nail-groove c of said shoe, while said die B has the exact size and shape of the finished shoe, and is provided with a rib, b, that has a Δ shape in cross-section, and is 55 adapted to complete said nail-groove c.

In practice a straight bar of iron is heated and placed over the die A in substantially a line with the transverse centers of the calk-recesses a' and a'', in which position said bar is 60 subjected to the action of an upper plain-faced die, D, and caused to fill the cavities of said die A. The partially-forged shoe C is now placed over the second die, B, and by means of one or more blows from said upper die is 65 forced into the former and given the exact shape required. As the metal under the action of the upper die must flow outward and downward in the preliminary die A, so as to fill the recess at such point and form the outer 70 thickest portion of the shoe C, it is necessary that the rib a should be low and transversely rounded, so as not to be an obstruction to the movement of the heated metal or to cause at such point a cold sheet.

75 In order that the shoes may be forged directly from a bar without first cutting the same into lengths, the upper die, D, has but slightly greater length than is necessary to enable it to cover the recesses in the dies A and 80 B, and in use its ends cut into said bar and nearly sever the metal, leaving at each end of the shoe C a sprue, c', that serves to connect said shoe with the previously-forged shoe in front and with said bar at its rear, and enables 85 a number to be forged at one heat from said bar without separation. While the corners of said die D are preferably left square, they may, if desired, be rounded or formed at any angle.

90 After the shoes C have passed through the finishing-die B, each is placed over a female trimming-die, E, that corresponds to the outline of the completed shoe, and is then operated upon by an upper male die, F, which 95 forces said shoe through said opening and removes all surplus metal from its edges. This trimming operation is performed without re-heating the metal.

100 The process described is not claimed herein,

as it forms the subject of a separate application for patent.

Having thus fully set forth the nature and merits of my invention, what I claim is—

5 1. A lower die provided with an intaglio for forming an ox-shoe, in combination with a plain-faced upper die having a length but slightly greater than the length of said intaglio and less than the length of the face of said 10 lower die, substantially as and for the purpose shown.

2. The blanking-die A, provided with the half-round rib *a*, in combination with the finishing-die B, having the A-shaped rib *b*, and

with a plain-faced upper die, substantially as 15 and for the purpose set forth.

3. The series of dies A, B, D, E, and F, constructed as described, and adapted for use in forging and trimming an ox-shoe, substantially as shown.

In testimony that I claim the foregoing I have hereunto set my hand this 26th day of August, 1884.

WILLIAM PEARCE.
